UNITED STATES PATENT OFFICE

111,552

DESIGN FOR A PRINTING TYPE FONT

Frederick H. Ernst Schneidler, Stuttgart, Germany, assignor to The Bauer Type Foundry, Inc., New York, N. Y., a corporation of New York

Application November 13, 1937, Serial No. 72,848

Term of patent 7 years

To all whom it may concern:

Be it known that I, Frederick H. Ernst Schneidler, a citizen of the Republic of Germany, residing in Stuttgart, Germany, have invented a new, original, and ornamental Design for a Printing Type Font, of which the following is a specification, reference being had to the accompanying drawing, forming part thereof.

The figure of the drawing is a face view of the printing type font showing the design.

I claim:

The ornamental design for a printing type font, as shown.

F. H. ERNST SCHNEIDLER.
